UNITED STATES PATENT OFFICE.

OTTO WOLTERS, OF MAGDEBURG, AND KARL HÖPER, OF BERLIN-CHARLOTTENBURG, GERMANY, ASSIGNORS TO SAID OTTO WOLTERS.

FEELING MECHANISM FOR MACHINES FOR PUNCHING CONTROLLING BANDS.

Application filed April 15, 1926, Serial No. 102,328, and in Germany June 6, 1925.

This invention relates to punching machines for punching controlling bands designed for controlling a line casting machine, said punching machines being of the 5 type described in our application Serial Number 721,524. This invention has for its object to improve the feeling mechanism described in said application so that only a few levers and a very simple mechanism 10 easy to survey are necessary.

With this object in view the marks on the circulating elements consisting of lateral incisions are not all of the same depth but of different depths so that by the position and 15 the depth of the incisions the desired combinations can be obtained. In this case four feeling elements are sufficient for adjusting the punching mechanism.

Spring-controlled feeling elements are 20 designed to engage with the incisions in the circulating elements and to regulate, by their movement, the amplitude of the oscillation of the punching levers. These punching levers are brought onto the path of a punching frame if they are in a certain position and they are carried along in this position 25 by the punching frame and punch holes into the controlling band. The punchings at different points of the controlling band correspond to certain characters which appear 30 on the key board of the punching machine.

A further object of the invention is, to 35 control the feeling elements by the separating slide. The function of this separating slide, as stated in our prior application Serial Number 721,524, is to push the elements separated from an assembled line singly towards the distributing spindles which convey the elements to the corresponding 40 magazines.

According to the invention the feeling levers bear against an abutment on the separating slide and are pressed onto the same by the action of springs. If the 45 separating slide is moved the feeling levers can engage with incisions, preferably arranged in the lower edge of the circulating elements, and adjust the abutments for the operation of the corresponding punches. 50 With this object in view the stroke of the separating slide is subdivided into two steps. At the first step it advances only so far that the feeling levers engage with the incisions of the circulating elements, at the second

step the separating slide pushes the circulating elements onto the path of the distributing spindles. The return stroke of the separating slide is continuous, the feeling levers being returned into the initial position.

The amplitude of oscillation of the punch levers is regulated by adjusting bands connected with the feeling levers and possessing apertures. In front of these adjusting bands spring-controlled bolts are arranged onto 60 which the punches are pressed by the action of springs. If the adjusting bands are displaced by a movement of the feeling levers so that an aperture comes into register with its bolt, this bolt traverses the band 65 in moving a corresponding punch lever so that it gets onto the path of the punching frame. As soon as this frame is pushed in a downward direction by a separate mechanism of the machine it drives the punch 70 through the paper band.

The improved feeling mechanism is shown, by way of example, in the accompanying drawing in which:

Fig. 1 shows in side elevation the distributing mechanism.

Fig. 2 is an end view of the separating slide and of the head of the feeling levers.

Fig. 3 is a section on line 3—3 of Fig. 1.

Fig. 4 is an end view of Fig. 1.

Fig. 5 shows in elevation the distributing mechanism and the transmission elements from the feeling levers to the punching mechanism.

Fig. 6 is a section on line 6—6 of Fig. 5.

Fig. 7 is a section on line 7—7 of Fig. 5.

Fig. 8 is a side elevation of Fig. 5.

On the shaft 1 connected with one of the distributing spindles 13 a curved cam-surface 3 is arranged which controls the oscillating movements of a lever 2. This lever 2 is permanently pulled to the left by the action of a spring 4 attached to the machine frame (Fig. 1). With lever 2 a second spring-controlled lever 5 is connected which carries on its front end a separating slide 6. In the separating slide 6, which is submitted to the action of a pressure-spring 7, the heads 8 of the feeling levers 12 are accommodated so that they bear onto a shoulder 6^a on the inner side of the separating slide. These heads 8 have each at the top end an extension 8^a of approximately

the same thickness as a circulating element. On the lever 5 a guide fork 9 is hingedly mounted the arms of which engage over a bolt 9^a. On the guide fork 9 an abutment 5 surface 10 is arranged against which bears the lower end 11^a of a locking lever 11. The other end 11^b of this locking lever strikes onto the lower lugs of the circulating element *a*, as can be seen from Fig. 4.

10 The feeling levers 12 are pivotally mounted on the machine frame and they are connected each one with a rod 14. These rods 14 are pulled downward by the action of springs 16 so that the heads 8 of the feeling levers 12 have a tendency to move in upward direction.

15 The operation of the elements of the mechanism which have been described is as follows:—By the curved cam surface 3 the lever 2 is operated which lifts the separating slide 6 through the intermediary of lever 5. As the heads 8 of the feeling levers 12 are under the action of the springs 16 they move together with the separating slide 25 6 and engage with the corresponding incisions *b* of the circulating elements *a* resting upon the surface 1^a. The end 11^b of the locking lever 11 supports the elements so that they cannot be raised by the feeling 30 lever. The locking lever 11 is prevented from rotating by the abutment face 10 of the guide fork 9. The extensions 8^a of the heads 8 penetrate into the incisions *b* of the circulating elements down to the end. The 35 lever 2, and through the same the separating slide is again operated by the second step of the curved cam surface 3 so that the abutment of surface 10 releases the locking lever 11 and the circulating elements *a* can be raised by the upper edge of the slide 6 into the path of the distributing spindles 13. (Fig. 4.) The curved cam surface 3 drops again and the separating slide 6 returns by its shoulder 6^a the heads 8 into the 40 initial position.

45 If the driving mechanism for the feeling levers has to be thrown out of gear for the reason that there are no circulating elements in the distributing mechanisms, or if the 50 transmission slide which conveys the line of assembled elements for the elevator into the mechanism is pulled back, the following arrangement is provided:

55 A lever 50 pulled to the right by the action of a spring 52 is pivotally mounted on a bolt 51 fixed in the machine frame. With this lever 50 a bow 53 is connected, as can be seen from Figs. 1 and 3, the curved front end of which engages with a notch of the 60 guide piece 57; the end of the bow is in the path of the rising circulating element *a*. The lower end 54 of lever 50 rests, in the normal position, upon the surface 55 of the feeling lever 12 and prevents thus the upward movement of the left lever arm. Close

65 to this surface 55 a notch 56 is arranged on the feeling lever 12.

The operation of this disengaging mechanism is as follows:—

70 By the spring 52 the top portion of the lever 50 is pulled to the right and the bottom portion 54 to the left so that this bottom portion prevents the movement of lever 12. As soon as a circulating element *a* is pushed into the guide piece 57 by one of 75 the conveying slides shown in our prior application Serial Number 721,524, it pushes the bow 53 in front of it, the spring 52 being thus put under tension. The end 54 of the lever 50 is thus brought into register with 80 the notch 56 of the feeling lever 12, so that this feeling lever can move upward as soon as the separating slide 6 is raised so that the feeling levers can come into engagement with the circulating elements *a*.

85

If there is no circulating element in the mechanism or if the conveying slide is just pulled back the feeling levers 12, if these disengaging means were not provided, would move with the separating slide and useless perforation combinations would be produced in the controlling band.

90

95 The transmission of the movement or of the extreme position of the heads 8 of the feeling levers 12 is controlled, as has been mentioned above, by the rods 14 (Figs. 5 to 8).

95

100 The lower ends of these rods act upon levers 15 which are connected with adjusting bands 17. These bands 17 have notches 18 and they are guided in corresponding slots of the machine frame. In front of the adjusting bands spring-controlled bolts 19 are arranged.

100

105 As soon as the adjusting band is shifted, if the lever 12 is in the extreme position, so that a notch 18 comes into register with one of the bolts 19, this bolt can traverse the adjusting bands 17 if it is pushed by one of the levers 20 towards said adjusting bands. The punch levers 20 are controlled by springs 21 which, as can be seen from Fig. 6, have the tendency to move said levers to the right. The springs 21 are much stronger than the springs of the bolts 19.

110

115 If one of the springs 21 can push the lever 20, and consequently the corresponding bolt 19 through the adjusting bands 17, this punch lever 20 gets into the path of the punching frame 22 and is drawn along by this frame as soon as it is depressed by a lever 24 moving in a curved guide groove of the main shaft 23. The descending movement of the punching frame 22 is transmitted through the intermediary of lever 20 upon the punch 25 which thus punches a hole into the controlling band 26. To a certain extreme position of the levers 12 corresponds therefore a certain punching of the controlling band.

120

125

130

In order to lock the adjusting bands 17 in their extreme position a separate mechanism is provided which consists of a two-armed lever 28 driven from the main shaft 23, and connected with a rod 20 which carries a lever 29 which has a ratchet tooth. This lever 29 is controlled by a spring 61 and released by the cam of shaft 23 through the intermediary of rod 60 so that it is free 10 to follow the pressure of spring 61, as soon as the levers 12 have assumed their extreme position.

In order that the punch levers 20 do not press permanently onto the bolts 19, but 15 only if the feeling off of the circulating elements *a* takes place, they are normally pushed to the left by an abutment 63, as can be seen from Fig. 6. This movement is initiated by the shaft 1 through the intermediary of a cam 33 and transmitted by the lever 34 upon an adjustable abutment 66 of the lever 65. This lever 65 is, like the punching mechanism, mounted in a stationary frame 62 and its movement is transmitted upon a lever 32 which consequently executes an oscillating movement, so that at certain periods the abutment 63 and through this the punch levers 20 are pushed to the left.

In the new distributing mechanism the feeling off of the circulating elements can take place during the separating of the several elements from the line of assembled elements. No special device is necessary for 35 this purpose and it is further not necessary to bring the circulating elements separately into a special position for feeling off. At the feeling off the circulating elements are held in all directions so that no special 40 means are required to support the elements from different sides during the feeling off. The mechanism works with a few levers only so that its effect is secured and easy to survey.

We claim:—

1. A feeling mechanism for machines for punching controlling bands, comprising in combination with a punching mechanism and with circulating elements having incisions of different depth, feeling levers designed to engage with said incisions of said circulating elements and a connection between said feeling levers and said punching mechanism designed to transmit the movements of said feeling levers to said punching mechanism.

2. A feeling mechanism for machines for punching controlling bands, comprising in combination with a punching mechanism and with circulating elements having incisions of different depth, feeling levers designed to engage with said incisions of said circulating elements, a connection between said feeling levers and said punching mechanism designed to transmit the movements

of said feeling levers to said punching mechanism, and a separating slide in which said feeling levers are located.

3. A feeling mechanism for machines for punching controlling bands, comprising in combination with a punching mechanism and with circulating elements having incisions of different depth, feeling levers designed to engage with said incisions of said circulating elements, a connection between said feeling levers and said punching mechanism designed to transmit the movements of said feeling levers to said punching mechanism, a separating slide in which said feeling levers are located, and a cam disk 75 controlling said separating slide.

4. A feeling mechanism for machines for punching controlling bands, comprising in combination with a punching mechanism and with circulating elements having incisions of different depth, spring controlled 85 feeling levers designed to engage with said incisions of said circulating elements, a connection between said feeling levers and said punching mechanism designed to transmit 90 the movements of said feeling levers to said punching mechanism, a separating slide in which said feeling levers are located, and an abutment on said separating slide designed to draw said feeling levers along and 95 to return the same to their initial position.

5. A feeling mechanism for machines for punching controlling bands, comprising in combination with a punching mechanism and with circulating elements having incisions of different depth and lugs, spring controlled feeling levers designed to engage 100 with said incisions of said circulating elements, a connection between said feeling levers and said punching mechanism designed to transmit the movements of said 105 feeling levers to said punching mechanism, a separating slide in which said feeling levers are located, an abutment on said separating slide designed to draw said feeling levers along and to return the same into their initial position, a locking lever, and an upper abutment on said locking lever designed to bear onto the lugs of said circulating elements.

6. A feeling mechanism for machines for punching controlling bands, comprising in combination with a punching mechanism and with circulating elements having incisions of different depth and lugs, spring controlled feeling levers designed to engage 110 with said incisions of said circulating elements, a connection between said feeling levers and said punching mechanism designed to transmit the movements of said 115 feeling levers to said punching mechanism, a separating slide in which said feeling levers are located, an abutment on said separating slide designed to draw said feeling levers along and to return the same into their initial position, a locking lever, an upper 120

125

130

abutment on said locking lever designed to bear onto the lugs of said circulating elements, and a fork hingedly mounted on said separating slide and having a guide face designed to serve as abutment for said locking lever.

7. A feeling mechanism for machines for punching controlling bands comprising in combination with a punching mechanism, 10 circulating elements having incisions of different depths, feeling levers designed to engage with said incisions of said circulating elements, a connection between said feeling levers and said punching mechanisms designed to transmit the movements of said 15 feeling levers to said punching mechanisms, a bow reaching into the path of said circulating elements, and a locking mechanism situated in front of said feeling levers connected with said bow and designed to lock 20 said feeling levers.

8. A feeling mechanism for machines for punching controlling bands comprising in combination with a punching mechanism, 25 circulating elements having incisions of different depths, feeling levers designed to engage with said incisions of said circulating elements and having notches, a connection between said feeling levers and said punching mechanisms designed to transmit the movements of said 30 feeling levers to said punching mechanisms, a bow reaching into the path of said circulating elements, and a locking mechanism situated in front of said 35 feeling levers connected with said bow and designed to lock said feeling levers upon engaging with said notches of said feeling levers.

9. A feeling mechanism for machines for 40 punching controlling bands, comprising in combination with a punching mechanism and with circulating elements having incisions of different depth, feeling levers designed to engage with said incisions of said 45 circulating elements, a connection between said feeling levers and said punching mechanism designed to transmit the movements of said feeling levers to said punching mechanism, a locking mechanism for regulating 50 the amplitude of oscillation of said feeling levers, and keys for operating said locking mechanism.

10. A feeling mechanism for machines

for punching controlling bands, comprising in combination with a punching mechanism 55 and with circulating elements having incisions of different depth, feeling levers designed to engage with said incisions of said circulating elements, a connection between said feeling levers and said punching mechanism 60 designed to transmit the movements of said feeling levers to said punching mechanism, adjusting bands having apertures, bolts in front of said adjusting bands and in front of said levers of said punching mechanism, and springs for pressing said bolts against said bands.

11. A feeling mechanism for machines for punching controlling bands, comprising in combination with a punching mechanism 70 and with circulating elements having incisions of different depth, feeling levers designed to engage with said incisions of said circulating elements, a connection between said feeling levers and said punching mechanism 75 designed to transmit the movements of said feeling levers to said punching mechanism, adjusting bands having apertures, a device for locking said adjusting bands, bolts in front of said adjusting bands and 80 in front of said levers of said punching mechanism, and springs for pressing said bolts against said bands.

12. A feeling mechanism for machines for punching controlling bands, comprising in 85 combination with a main driving shaft, a punching mechanism and with circulating elements having incisions of different depth, feeling levers designed to engage with said 90 incisions of said circulating elements, a connection between said feeling levers and said punching mechanism designed to transmit the movements of said feeling levers to said punching mechanism, adjusting bands having apertures, bolts in front of said adjusting bands and in front of said levers of said 95 punching mechanism, and springs for pressing said bolts against said bands, a locking hook for said adjusting bands, and means for operating said locking hook from said 100 main shaft.

In testimony whereof we affix our signatures.

OTTO WOLTERS.

KARL HÖPER.
